pair of inner grooves 47 are formed in the inner surface 32 of housing body 30 in laterally spaced relation with respect to each other, each adjacent to and inward of a respective outer groove 45, and extending vertically from its lower end opening into the slot 33 to an upper end region 48 which extends laterally inward, spaced below the adjacent slot region 46 and opening into the lower region of recess 38. On opposite sides of the recess 38, each body 30 is formed with a pair of through apertures or holes 50 for receiving the fasteners 27, as will become apparent hereinafter.

As best seen in Figures 2 and 3, the above-described contour or configuration of the inner body face 32 is substantially symmetrical about a vertical center line, the boss 42 being located on the center line, with each pair of shoulders 40, apertures 50, and grooves 45 and 47 being equally spaced on opposite sides of the center line. By this construction, the housing sections 26 are interchangeable with each other, to greatly simplify manufacture and assembly.

As a pair of housing sections 26 are secured fast to each other by the fasteners 27 with their inner surfaces 32 in facing engagement, it will be understood that the slots 33 of the secured housing sections open toward each other to define an elongate through opening for receiving the electric line 21. Further, the facing recesses 38 combine with each other to define an internal hollow spaced from the opening 33 and opening upward away from the latter, while the bosses 42 may meet or approximately so, in end-to-end relation, to define a pivot pin or shaft. Also, the outer grooves 45 of each housing body 30 combine with the outer grooves of the other housing body to define a pair of outer passageways each opening at its lower end into the opening 33 and extending generally vertically therefrom to its upper end region 46 which extends laterally inward in divergent configuration and opens into the recess 38. Similarly, each groove 47 of one housing body 30 faces toward and combines with a respective groove 47 of the other housing body 30 to define a passageway located adjacent to and inward of a respective passageway 45, opening at its lower end into the opening 33 and extending laterally inward at its upper end region 48 for communication with the recess 38 at a lower region thereof.

The switch element 23 may be fabricated of any resilient conductive material, such as Phosphor bronze or the like, and is bent to a generally L-shaped configuration, as best seen in Figure 9. An intermediate portion of the conductive strip 23 is received in the vertical portion of one passageway 47, the left-hand passageway 47 as seen in Figure 2, and has its upper region extending laterally therefrom through the upper passageway end portion 48, to the right across the lower region of recess 38 and into the opposite upper passageway region 48. The upper portion 51 of the strip element 23 thus extends between and has its opposite ends received and supported in opposite passageway portions 48. Projecting downward from the intermediate, generally vertical portion of strip element 23 is a lower end or connection portion 52. This lower end or connection portion 52 is of a bifurcated configuration, best seen in Figures 5 and 9, and depends or projects into the opening 33 on one side of the longitudinal center line of the opening. That is, the connection portion 52 is offset laterally from the longitudinal center line of the strip element 23, and as the latter is substantially equally received in each of the mating grooves 47, the connection portion 52 is offset laterally with respect to the center line of the passageway defined by the latter grooves, and also with respect to the opening 33. This laterally offset relationship of the connection 52 with respect to the longitudinal center line of the opening 33 may best be seen in Figure 5.

An additional conductive strip 24 has an intermediate portion conformably received in the passageway 45 on

the left-hand side as seen in Figure 2, and has its upper end portion 55 extending laterally inward through the divergent upper passageway portion 46 into the recess 38 over the upper end portion 51 of the strip 23. The strip 24 has its upper end portion 55 bent or crimped at spaced locations 56 and 57 to form holding recesses, as will appear presently, and by its inherent resilience is normally biased upward away from the strip portion 51, but resiliently deflectable into engagement with the latter. Thus, the strip portions 51 and 55 are relatively movable into and out of contacting engagement with each other, and as will appear more fully hereinafter, serve as switch elements for closing and opening the switch circuit upon their engagement and disengagement.

As best seen in Figures 4 and 9, a lower end portion 58 projects from the vertical intermediate portion of the switch element or strip 24 into the opening 33, and is offset laterally from the longitudinal center line of the switch element so as to be offset laterally from the longitudinal center line of the housing opening. Further, the end projection or extension 58 of the switch element or strip 24, which is of a depending bifurcated configuration similar to that of the end portion 52 of switch element 23, is offset so as to lie on the opposite side of the opening 33, or more specifically on the opposite side of its longitudinal center line, as the projection 52, in the condition of Figures 1-5 and 9. Thus, as viewed from the same direction in Figures 4 and 5, the lower end projection 52 of the switch element 23 is offset to the right, while the lower end projection 58 of the switch element 24 is offset to the left.

The actuating member 22 is located generally in the recess 38 and includes a pair of laterally oppositely extending arms 60 each located adjacent to and above a respective shoulder 40. Intermediate the arms 60, the actuating member 22 may be provided on its opposite face with a pair of aligned blind bores or recesses 61, which may meet to define a through bore, if desired, and receive the bosses 42 to mount the actuating member 22 for pivotal movement about the axis of the aligned bosses. Depending from the actuating member intermediate the arms 60 into a lower region of the recess 38 is a tapered extension or leg 62. The actuating member 22 is swingable about its pivotal axis between the limiting position of Figure 1 with the right-hand arm 60 engaging the right-hand shoulder 40, and the position of Figure 3 with the left-hand arm 60 engaging the left-hand shoulder 40. The upper end or contact portion 55 of the switch element 24 is resiliently biased upward into engagement with the sharp but rounded end of the extension 62; and, in the limiting position of Figure 2 the extension 62 is releasably retained in position by interengagement of its lower end in the upwardly facing recess or bent portion 56 of the contact strip portion 55, while the actuating member is releasably retained in the position of Figure 3 by interengagement of the extension 62 in the upwardly facing recess or bend 57 of the strip-element contact portion 55. Thus, the actuating member 22 is releasably retained in a selected one of its extreme or limiting positions of pivotal movement. In the condition of Figure 2, it will be noted that the contact portion 55 is depressed downward or moved into engagement with the contact portion 51, such engagement causing the latter contact portion to be deflected slightly downward to insure contact between the engaging portions. However, upon depression of the left-hand actuating-member arm 60 to effect counterclockwise rotation thereof, the lower end of extension 62 rides out of the recess or bend 56 along the contact portion 55 into the recess or bend 57 which permits upward movement of the contact portion 55 by its inherent resilience away from and out of engagement with the contact portion 51, to the position of Figure 3.

In assembling the instant switch with an electric line 21, which is advantageously of two-conductor wire, as at

65 and 66, the line end is first inserted into one end of the opening 33, which may be the left-hand end as illustrated, or otherwise if desired. The opening 33 is of a lateral elongation or extent sufficient to receive the two-conductor line 21 in a substantially horizontal condition. That is the line 21 is inserted into the opening 33 with the line conductors in side-by-side relation. The opening 33 is also of a sufficient vertical extent to permit insertion of the line 21 below and past the depending projections 52 and 58 without obstruction by the latter. With the end of line 21 thus inserted in opening 33, a holding member, bar or wedge 67 is forcibly inserted into the opening beneath the electric line. Such insertion of the holding member 67 forces the electric line 21 upward in the opening 33 causing the insulation of conductors 65 and 66 to be respectively pierced by the projections 52 and 58. This effects firm electrical connection between the conductors 65 and 66 with the respective switch elements 23 and 24; and, the adjacent fingers 36 are embedded in the insulation of the electric line to prevent withdrawal of the latter from the opening 33 and minimize the transmission of a pulling force on the electric line to the switch elements. Insertion of the holding member 67 entirely into the opening 33, as illustrated, effectively prevents disconnection of the switch from the electric line, as a special tool is required to remove the holding member.

It is now, of course, appreciated that the instant switch in the condition of Figure 2 provides a closed circuit between the conductors 65 and 66, while serving to open such circuit in the condition of Figure 3, in the manner of a pendant switch.

Substantially the same structural elements are shown in Figures 6-8 employed as a line or feed-through switch. In such figures, the same elements are employed, with the only exception being that a relatively long holding member or bar 67a is inserted into the opening 33. There is a very slight rearrangement of parts in that the switch element 23 is received in the right-hand groove or passageway 47, having its upper or contact portion 51 extending leftward into the upper portion 48 of the left-hand passageway 47. This inversion or reversal of the switch element 23 serves to shift its lower end projection or connection portion 52 into alignment with the lower end projection or connection portion 58 of the switch element 24, longitudinally of the opening 33, as may be seen in Figure 8. Thus, the connection portions 52 and 58 of the switch elements 23 and 24 are offset on the same side of the longitudinal center line of the opening 33 for electrical connection to the same conductor 66a of the electric line 21a received in and extending through and out of opposite ends of the opening 33. Of course, a portion of the conductor 66a is cut away, as at 69, which cutout portion is located between the connection portions 52 and 58, so that the conductor 66a is open when the switch is open, and electrically closed when the switch is closed.

It will now be appreciated that the instant switch is capable of use as both a pendant and a line or feed-through switch by equally simple connections to the electric line. Although only a single rearrangement of the switch element 23 has been illustrated to transform the instant switch from its pendant to its feed-through condition, it is believed obvious that other arrangements of the switch elements may be employed, if desired, for either type operation. Further, additional rearrangements may be effected by reverse bending of the switch elements, as by bending the vertical portion of switch element 23 upward, and turning such switch element over so that its use in the right-hand passageway 47 would produce a pendant-type switch.

In Figures 10-12 are shown a switch constructed in accordance with the present invention, wherein the housing sections 26b are substantially the same as the housing sections 26 described hereinbefore, with the exception

that the through housing passageway 33b, corresponding to the passageway 33, opens downward from the housing 20b, and each of the housing sections is provided along its lower edge with a longitudinally extending, outstanding flange 71. In order to close the underside of the opening 33b, there is provided a channel 72 having inturned, longitudinally extending upper-edge lips 73 which is removably slidable with the flanges 71 received beneath the lips 73 into covering relation with the opening 33b. By this construction, the holding members 67 and 67a of the above-described embodiments may be eliminated; and, both pendant and feed-through-type connections may be quickly and easily made and changed by unskilled persons and without special tools.

With the channel or cover 72 removed, as in dot-and-dash outline in Figure 10, it is only necessary to insert an electric line 21 in the opening 33b, and replace the cover by sliding movement on the flanges 71, to achieve the connected condition of Figures 11 and 12. Further, connection for feed-through use is facilitated by the embodiment of Figures 10-12, as the line insertion may be made laterally, rather than endwise.

As the only moving part in the switch of the instant invention is the pivoted actuating member 22, an extremely simple and inherently long-lasting and reliable operation is assured. The contact switch element portions 51 and 55 are, of course, flexed only within their elastic limit, so that repeated opening and closing of the switch over a long period of time causes no damaging effects. If it is desired to completely minimize wear of the extension 62 by its movement along the contact portion 55, this may be accomplished by an actuating member 22a shown in Figures 13 and 14. This actuating member is substantially the same as the actuating member 22 described hereinbefore, except that a relatively wear-resistant tip 75 is provided on the lower end of leg or extension 62a. Such a tip may take the form of a cylindrical rod, as illustrated, embedded or otherwise captively held in the lower end of the leg 62a. If desired, the rod 75 may roll for rolling, rather than sliding engagement with the contact portion 55.

In the embodiment of Figures 15-18, the switch illustrated therein includes a housing or casing, generally designated 120, and is connected to an electric line 121. A pivotal actuating member, in the nature of a rocker arm 122 is mounted in the housing 20, extending exteriorly thereof, and a pair of electrically conductive switch elements or strips 123 and 124 are mounted interiorly of the housing for electrical connection to the line 121 and operatively connected to the actuating member 122 for selective engagement and disengagement of the switch elements with respect to each other.

The housing 120 includes a pair of substantially identical, complementary parts, halves or sections 126 secured in facing engagement with each other, as by through rivets 127, or other suitable fasteners. The complementary housing sections 126 are each preferably molded as an integral unit of plastic or other suitable insulating material, and consists essentially of a generally platelike body 130 of approximately rectangular-outline configuration and having a substantially flat outer surface 131. The inner face 132 of each body 30 is substantially parallel to the outer face 131 thereof, and is preferably formed with a slot or groove 133 extending longitudinally of the lower body edge 134, adjacent to and spaced from the latter, and opening at its opposite ends through opposite side edges 135 of the housing body. Formed in the slot 133, on the upper internal surface thereof and adjacent to opposite slot ends, are a plurality of internal projections, teeth or serrations 136, for retaining engagement with the line 121.

In the upper region of each body 130, spaced from the slot or groove 133, the inner surface 132 is formed with a recess 138 opening upward or outward through the upper body edge 139. The lower central part of

the recess 138 is of reduced lateral extent, as at 141 between a pair of laterally spaced, upwardly facing shoulders 140. As best seen in Figure 18, a generally cylindrical boss or stub shaft 142 projects into the recess 138 adjacent to the upper body edge 139 in a laterally medial region.

Extending about the exterior of the housing body 130, along the upper body edge 139, preferably adjacent to but spaced from the latter, is an external rib, shoulder or ridge 143.

Also formed in the inner body surface 132 are a pair of laterally spaced grooves 145, each extending generally vertically having its lower end opening downward into the slot 133, and having its upper end opening upward through a respective shoulder 140 into the recess 138. Each groove or slot 145 is interrupted in its vertically medial region by an internal shoulder 146; and, a relatively shallow recess 147 extends laterally from each groove 145 inward to the lower recess portion 141, opening vertically upward through the shoulder 140 and downward into the slot 133.

A pair of fastener-receiving apertures or holes 150 are formed through each housing body 130 adjacent to and laterally outward of the grooves 145.

In this embodiment, as in the first-described embodiment, each of the housing bodies is substantially symmetrical about a vertical center line, so that the housing sections or bodies are interchangeable with each other.

In assembly, a pair of housing sections 126 are secured fast to each other by the fasteners 127 with their inner surfaces 132 in facing engagement, so that the slots 133 of the facing housing section open toward each other and define an elongate through opening for receiving the electric line 121. Also, the facing recesses 138 and their reduced lower portions 141 of the secured housing sections combine with each other to define an internal hollow spaced from the opening 131, and the grooves 145 of one housing section combine with respective facing grooves 145 of the other housing section to define a pair of passageways each extending generally vertically and opening at its lower end into the opening 133 and at its upper end into the hollow 138.

The switch element 123, which may be of any suitable conductive strip material, includes an intermediate portion which is received in one passageway 145; and, the intermediate strip portion is provided with opposite side notches or cutouts 149 respectively receiving the passageway shoulders 146, as best seen in Figure 17. The upper portion 151 of the strip element 123 extends laterally inward closely overlying the adjacent shoulder 140, extending therebeyond into the lower hollow region 141. The extending upper end portion 151 of the strip element 123 may be upwardly dimpled, as at 153 to define a contact area. Projecting downward from the intermediate, generally vertical portion of strip element 123 is a lower end or connection portion 152. This lower end or connection portion may be of a pronged configuration, and depends or projects into the opening 133 on one side of the longitudinal center line of the opening, being offset laterally from the longitudinal center line of the strip element.

The conductive strip 124 has its intermediate portion formed with a pair of laterally spaced cutouts or openings 154 extending inward from opposite side edges of the strip, and is received in the other groove or passageway 145, the right-hand passageway as seen in Figure 16, with the shoulders 146 engaging in the cutouts 154. The upper end portion 155 of the strip 124 extends laterally inward over its adjacent shoulder 140 into the lower recess portion 141, and is provided with a pair of laterally extending, longitudinally spaced recesses 156 and 157, which face generally upward and are defined by bends in the strip. The distal end of the upper strip portion 155 is located over the distal end of the other upper strip portion 151, and preferably there provided

with a downwardly extending dimple 163. The dimple 163 is engageable with the dimple 153 upon movement of the strip portion 155 toward the strip portion 151.

5 A lower end portion 158 of the switch element 124 depends into the opening 133 and is offset laterally from the longitudinal center line of the switch element, so as to be offset laterally from the longitudinal center line of the housing opening. The lower end portion 158 may be pronged or bifurcated as illustrated, for piercing engagement through the insulation of line 121, as in the first-described embodiment.

10 As illustrated in Figures 16-19, the projecting ends or connection portions 152 and 158 of the switch elements 123 and 124, respectively, are offset laterally of the opening 133 in the same direction, for electrical connection with the same conductor 166 of the electric line 121. As described hereinbefore, this arrangement is employed in using the device as a feed-through or line switch. It will now be readily understood that the embodiment of Figures 15-19 may be employed as a pendant switch by merely forming one of the switch elements 123 or 124 with its depending connection portion 152 or 158 offset laterally on the other side. In this case, one of the connection elements will electrically connect with the line conductor 166, and the other connection element will electrically connect with the line conductor 165.

15 The actuating member or rocker 122 is similar to the actuating member 22, being received in the recess 138 and pivotally mounted therein by reception of the bosses 142 in its hole 161. The actuating member 122 includes oppositely extending arms 160 and a depending extension or leg 162 which carries in its lower end a wear-resistant member or rod 175. The actuating member 122 is rotatable between extreme limiting positions with its arms 160 in abutting engagement with their respective adjacent shoulders 140, the lower end of leg 162 being respectively engageable in the recesses 156 and 157 in the extreme limiting positions of rotative movement. In the illustrated condition of Figure 16, the switch elements 123 and 124 are closed or in engagement with each other, while counterclockwise rotation of the actuating member 122 to its other limiting position permits the upper end portion 155 of switch element 124 to move upward under its inherent resilient force away from the upper end portion 151 of switch element 123.

20 The switch of Figures 15-19 is assembled with its electric line 121 in substantially the same manner as the hereinbefore described embodiments, the line being inserted into the passageway 133, and a holding member, bar or wedge 167 being inserted in the passageway beneath the electric line to force the latter upward against the switch-element connection portions 152 and 158, and against the holding serrations or teeth 136. In this manner, the switch-element connection portions are electrically connected to the desired conductor or conductors of the electric line. It will be noted that upward force applied by the electric line to the switch elements 123 and 124 is resisted by the interengagement of the switch elements with the shoulders 146, in contrast to the first-described embodiment, wherein such upward force is resisted by the upper end portions of the strip-receiving passageways.

25 In the embodiment of Figures 15-19, it will be noted that the recesses or grooves 156 and 157 are disposed in contiguous relation, particularly as compared to the spaced grooves 56 and 57 described hereinbefore. In the previously described embodiment, positive actuation of the rocker 22 is required to shift the latter between its on and off positions, to overcome friction of the leg 62 against the movable contact portion. However, in the last-described embodiment, it is only necessary that the center of the rocker leg rod 175 pass slightly beyond the crest defined by the juncture of the contiguous recesses 156 and 157. At this moment, the resilience of the

switch-element contact portion 155 causes the rocker leg rod 175 to snap into the other of the recesses 156 and 157. Thus, the switch of Figures 15-19 is quick and sure-acting, and cannot retain itself in an intermediate position between on and off.

In the assembled condition of a pair of substantially identical housing bodies or sections 130, it is understood that the beads or shoulders 143 of the respective sections combine with each other to extend peripherally about the entire housing. The thus-defined peripheral bead or shoulder 143 may provide an abutment advantageous in the panel mounting of the instant switch, as seen in Figure 15. It will there be observed that a panel 170 is formed with a through opening 171 adapted to conformably receive the upper end portion of the switch housing 120 with the abutment or bead 143 bearing against the rear face of the panel. A suitable, apertured retainer plate 172 may be engaged about the switch housing 120 on the rearward side of and in engagement with the abutment 143, and there retained in position by fasteners 173 extending into the panel, to quickly, easily and firmly mount the switch housing in the panel.

While the fasteners 27 and 127 employed to hold the housing sections 26 in their facing engagement have been illustrated as rivets, it is appreciated that other fastening means may be employed, if desired. In particular, if the switch is to be permanently assembled, the manufacturer may arrange the parts in the required assembled relation for the desired type of switch, either pendant or feed-through, and secure the housing sections by rivets. If the type of switch, either pendant or feed-through, is to be optional and convertible as desired by the user, detachable fasteners, such as screws and nuts, may be employed rather than rivets.

Although the electric lines illustrated in the various embodiments of the present invention have been shown as solid conductor wire, it is understood that stranded wire may be employed, if desired. Also, the depending projections or connection portions of the switch elements need not be bifurcated, but may, if desired, consist of a single impaling point.

From the foregoing, it is seen that the present invention provides a switch construction which is highly versatile in use, otherwise fully accomplishes its intended objects, and is well adapted to meet practical manufacturing and operating conditions.

Although the present invention has been described in some detail by way of illustration and example for purposes of clarity of understanding, it is understood that certain changes and modifications may be made within the spirit of the invention and scope of the appended claims.

It is understood that the term "electric line" is intended to comprehend the various types of conductors capable of being employed in conjunction with the switch of the instant invention, and to be inclusive of the terms "insulated wire," "insulated conductor," "line cord," "two-conductor parallel wire," and the like.

What is claimed is:

1. An electric switch comprising a housing having an elongate opening therein for snugly receiving a plural-conductor line, a pair of conductive switch elements mounted in spaced relation in said housing and having contact portions spaced from said opening and relatively movable into and out of engagement with each other, a connection portion extending from each of said switch elements into said opening for electrical connection with said line, said connection portions being in alignment with each other longitudinally of said opening and offset from the longitudinal center line thereof for connection to the same conductor of said line, one of said switch elements being reversibly mounted in said housing to locate its connection portion on the opposite side of the longitudinal center line of said opening as the connection por-

tion of the other switch element, for electrically connecting said connection portions with respective conductors of said line, and manually actuatable means movably mounted in said housing and operatively connected to the contact portion of at least one of said switch elements for effecting relative movement of said contact portions into and out of engagement with each other.

2. An electric switch comprising a housing having an elongate opening therein for snugly receiving a plural-conductor line, a first conductive strip mounted in said housing having at one end a first connection portion projecting into said opening at one side of the opening center line for connection to one conductor of said plural-conductor line and having a contact portion at its other end spaced from said opening, a second conductive strip having a second connection portion at one end and a second contact portion at its other end, means in said housing for mounting said second strip with said second contact portion adjacent to and spaced from said first contact portion and said second connection portion on a selected side of said opening center line for connection to a selected conductor of said plural-conductor line, and manually actuatable means movably mounted in said housing and operatively connected to the contact portion of at least one of said strips for effecting relative movement of said contact portions into and out of engagement with each other.

3. An electric switch according to claim 2, in combination with a holding element releasably carried by said housing for holding said line in electrical connection with said switch elements.

4. An electric switch according to claim 3, said holding element comprising an insert snugly engageable in said opening.

5. An electric switch according to claim 3, said opening being defined by an external groove in said housing, and said holding element comprising a cover removably engaged with said housing in covering relation with said groove.

6. An electric switch according to claim 2, in combination with an insert removably engaged in said opening spaced from said strip connection portions for maintaining said plural-conductor line in electrical connection with said strip connection portions.

7. An electric switch comprising a pair of substantially identical housing sections secured in facing engagement with each other; each of said sections having its facing surface contoured symmetrically about a center line and formed with an open-ended slot, a recess spaced from said slot and opening through one side of its housing section away from said slot, and four grooves each opening at its opposite ends into said slot and recess; the slots of said pair of sections combining to define a through opening for receiving a plural-conductor line, the recesses of said pair of sections combining to define an outwardly opening hollow spaced from said opening, and the grooves of said pair of sections combining to define four passageways each communicating between said opening and hollow; a pair of conductive strips each having a contact portion at one end and a connection portion projecting from the other end offset from the longitudinal center line of the respective strip, said strips being selectively disposed in said passageways with their contact portions in said hollow to position their connection portions for selective connection with the conductors of said plural-conductor line; and manually actuatable means movably mounted in said hollow and engageable with the contact portion of one of said strips to move the latter into and out of engagement with the contact portion of the other of said strips.

8. An electric switch according to claim 2, said opening defining an open ended internal passageway of closed cross sectional configuration, said strip connection portions projecting into said passageway from one internal side thereof and terminating short of the opposite internal

passageway side a distance sufficient to receive a plural-conductor line inserted in said passageway along said opposite internal passageway side, and an elongate holder element removably engageable in said passageway adjacent to said opposite internal passageway side for maintaining said plural-conductor line in connection with said connection portions.

9. In a wiring device, a housing having an elongate internal passageway for receiving electric line, at least one conductive strip mounted in said housing and having a connection portion projecting into said passageway from one internal side thereof and terminating short of the opposite internal passageway side a distance sufficient to receive electric line inserted into said passageway along said opposite internal passageway side, and an elongate

5 10 15

holding element insertable into said passageway along said opposite internal passageway side for displacing electric line away from said opposite internal passageway side into connection with said connection portion.

10. A wiring device according to claim 9, said passageway being generally rectangular in cross section, and said holding element being of elongate generally rectangular cross sectional configuration and having one end tapering to facilitate insertion into said passageway.
